UNITED STATES PATENT OFFICE.

ELIZA JANE LYNCH, OF NEW YORK, N. Y.

DESIGN FOR A CHILD'S BONNET.

SPECIFICATION forming part of Design No. 19,424, dated November 12, 1889.

Application filed March 21, 1887. Serial No. 231,779. Term of patent 3½ years.

To all whom it may concern:

Be it known that I, ELIZA JANE LYNCH, of New York, in the county of New York, and in the State of New York, have invented a 5 certain new and useful Design for a Child's Bonnet; and I do hereby declare that the following is a full, clear, and exact description thereof, reference being had to the accompanying drawing, in which is shown in side ele- 10 vation a bonnet of my design.

The principal feature of my design consists in the general shape of the bonnet, its front being composed of a part A, which extends from the bottom at each side straight 15 upward to and over the top. The back of the bonnet is composed of a part B, that extends from the rear edge at each end of the front A upward and rearward, while the crown is composed of another part C, which, from the 20 rear edge of said front and the upper edge of said back, extends upward and rearward with a rounded or dome shape, as shown.

Another feature of my design consists in narrow parallel rows of plaits *a*, which are 25 upon and extend lengthwise of the front A, as shown.

Another feature of my design consists of narrow parallel rows of plaits *b*, which are upon the back B and extend from its lower 30 edge to its upper edge, as shown.

Another feature of my design consists of a ruffle D, which extends around the entire front and bottom edge, as shown.

Another and the last feature of my design consists of two rearwardly-extending ruffles 35 E, which are upon the front A, immediately in rear of the ruffle D, and extend up the sides and across the top of said front.

Having thus described my invention, what I claim is—

The design for a bonnet, consisting of the part A, which constitutes a portion of the sides and top, the part B, which constitutes the back and is connected to the rear edges of the lower portions of part A, the rounded 45 or dome-shaped crown C, the ruffles D, extending around the front and bottom edges of the bonnet, and the rearwardly-pointing ruffles E behind or in rear of the ruffles D, substantially as described and shown.

In testimony that I claim the foregoing I have hereunto set my hand this 19th day of March, 1887.

ELIZA JANE LYNCH.
